pany, Cleveland, Ohio, a corporation of Ohio

Application December 21, 1950, Serial No. 202,052

12 Claims. (Cl. 153—48)

1

This invention relates to metal forming presses and particularly to a combination forming press and tangent bender.

Heretofore much difficulty has been encountered in the production on forming presses of cabinets and the like having planar side or peripheral walls which are portions of a single elongated sheet of metal bent about axes extending transversely of the sheet.

The difficulty arises principally from two factors. One is that, during the forming operation, the side walls of the cabinet portion frequently extend above the level of the die bed at each side of the ram to such an extent that the ram must be raised to a position far above its forming position in order to permit unloading of the formed portion laterally of the ram. The disadvantages of such long ram travel are apparent.

Again, it often happens that all or portions of the rear wall of the cabinet are formed integral with the side walls, in which case the rear wall, or lateral margins thereof, overhang the ram, or portions thereof or of the die carried thereby, so that the formed portion cannot be removed laterally of the ram.

Accordingly, to overcome these objections, attempts have been made heretofore to form such cabinets in presses in which the ram is supported only from one end so that the partially formed article can be removed endwise of the machine from the opposite or free unsupported end of the ram. However, in the latter instances, the long unsupported overhang of the ram results in deflection which progressively increases from the supported end of the ram to the free end.

To overcome this objectionable deflection, presses have been provided in which the ram, though normally supported at both ends, detachably engages the supporting column at one of its ends so that it can be released and swung laterally about the supporting column at the other of its ends out of its normal path of travel to permit removal of the formed stock endwise of the ram. In such a structure both columns are connected to power means for lifting and lowering so as to lift and lower the ram.

The latter type of machine is objectionable because of the time and work required to swing the ram laterally from a position above the die bed to the unloading position. Another objection resides in the fact that considerable floor space is required at one side of each forming press to accommodate the ram when it is swung out of its normal position above the bed. In

2

other respects it is inconvenient and time consuming from the standpoint of shop layout and flow of production. Again, no efficient means is provided for applying power equally to both ends of the ram.

In accordance with the present invention, the press is provided with a ram which is permanently supported from one end above the die bed and is operated by power means to move it downwardly close to the final forming position while supported only by the one end. Additional power means are provided and are equipped with suitable latch means normally positioned below or close to the level of the bed and which, when the ram is lowered close to working position, latch to both ends of the ram and draw the ram firmly into final position with equalized pressure at the ends. The machine is further provided with one or more wing dies, of the type commonly used in so-called tangent benders, such as described in U. S. Patents Nos. 2,287,933, issued June 30, 1942, and 2,446,824, issued August 10, 1948.

As a result, an elongated sheet of metal can be formed into the front wall, two side walls, and all or part of the rear wall of a cabinet, even though, when so formed, portions overhang all or part of the ram, and can be removed readily from the space between the ram and the die bed by moving it endwise from the end of the ram while the ram remains in alignment with the bed.

For purposes of illustration, our invention is disclosed as applied to a combination forming or bending press and single wing tangent bender in which it has special advantages, its use in connection with other types of presses and double wing tangent benders being readily apparent from the illustrative example.

The more specific objects and advantages of the invention will become apparent from the following description wherein reference is made to the drawings, in which:

Fig. 1 is a perspective view of a combined press and single wing tangent bender embodying the principles of our invention;

Fig. 2 is an enlarged cross sectional view of the apparatus illustrated in Fig. 1, and is taken on the line 2—2 of Fig. 4;

Fig. 3 is an enlarged right side elevation of the machine illustrated in Fig. 1, part thereof being shown in section for clearness in illustration;

Fig. 4 is an enlarged top plan view of the machine illustrated in Figs. 1 through 3;

Figs. 5 and 6 are fragmentary sectional views

taken on the lines 5—5 and 6—6, respectively, of Fig. 3;

Fig. 7 is an enlarged fragmentary cross sectional view of the apparatus illustrated in Fig. 1 and is taken on the line 7—7 of Fig. 4;

Fig. 8 is a fragmentary elevational view of the machine as viewed from the line 8—8 of Fig. 7, part thereof being shown in section for clearness in illustration;

Fig. 9 is a diagrammatic illustration of the fluid pressure and electrical circuits for controlling the operation of the apparatus illustrated in Figs. 1 through 8;

Fig. 10 is a side elevation of a modified form of the apparatus embodying the present invention; and

Fig. 11 is an enlarged fragmentary sectional view of the ram latch connection illustrated in Fig. 10.

Referring first to Figs. 1 through 8, the machine comprises generally a rigid frame 1 having an upwardly facing horizontal die bed 2 on which are mounted suitable forming dies 3. Mounted in fixed position in one end of the frame is an upright rigid guide column 4 which slidably supports a ram 5, the ram 5 being slidably connected by one of its ends to the column 4. The ram carries a plurality of forming dies 6 which are complementary to the dies 3, respectively.

For supporting the ram on the column 4, the ram is provided at its supported end with a rigid bearing sleeve 7 having internal slide bearing bushings 8. In the form illustrated, the column 4 is in the form of a hollow shaft of circular cross section. Consequently, in order to prevent swinging of the ram 5 about the axis of the column 4, a laterally extending lug 9 is secured in fixed position on the sleeve 7. The lug 9 has an upright bore in which an upright guide rod 10 is fixedly secured and from which it depends. Mounted in the frame 1 is a guide bearing 11 which slidably accommodates the rod 10 thus restraining the ram 5 from rotation about the axis of the column 4 in all vertical positions of the ram.

In order to raise the ram to its fully raised position and to lower it at least near to the forming position, a suitable reversible fluid pressure operated piston and cylinder assemblage is provided. The assemblage may comprise a piston 12 which is fixedly secured to the ram and a cylinder 13 which is secured within the frame 1 below the level of the bed 2. The assemblage is such that the ram can be raised thereby to fully open position or lowered to, or almost to, forming position very rapidly while guided on the column 4 and by the rod 10.

The opposing end of the ram is entirely free and, when the ram is raised a short distance from forming or closed position, affords adequate space between the ram and the bed for removal of any articles formed between the dies even though they are peripherally closed or extend around or partially overhang the ram or the dies carried thereby.

In order to move the ram into final forming position with equalized pressure at its ends, the mechanism now to be described is provided.

Mounted on the ram adjacent its free end 70 is a suitable latch element 15 which is connected to the ram by a pivot 16 extending endwise of the ram. The latch element 15 depends from its pivot 16 when in latching position, as illustrated in Fig. 2. Similarly, as best illustrated

in Fig. 6, at the opposite end of the ram 5, adjacent the sleeve 7, the ram is provided with a rigid or integral depending latch element 17 having a passage 18 therethrough near its lower end.

Within the frame 1 is a bifurcated lever 19 having arms 20 which are divergent from near one end of the lever 19 toward the opposite end. The free end of one arm 20 is near the free end of the ram 5 and the free end of the other is near the supported end of the ram 5. Referring to the former one of the arms 20, it is pivotally connected near its free end to the frame by means of a suitable yoke 21 and pivot 22, this pivotal connection preferably being adjacent to the free end of the ram 5 and the yoke preferably being connected to the bed of the frame so that reactance forces due to operating pressure applied to the lever 19 are in opposition to the operating pressure applied by the ram.

Mounted on this one of the arms 20 which is adjacent the free end of the ram is a generally upright complementary latch element 23 which is arranged for cooperation with the latch element 15.

As illustrated, the latch element 23 is connected by a pivot 24 to its associated arm 20 between the free end of its arm 20 and the pivot 22. The element 23 extends upwardly through a suitable opening in the bed of the frame, as best illustrated in Fig. 2, to a level a short distance above the bed 2. Mounted on the bed 2 at the free end of the ram 5 is a guide plate 25 having an upwardly open guideway 25a for receiving the lower portion of the free end of the ram 5 and guiding it along the lower portion of its path of travel so as to prevent lateral deflection of the free end of the ram. In order to retain the latch element 23 in a proper adjusted position for cooperation with the latch element 15, there is mounted on the guide plate 25 an adjustable abutment 26 which is arranged at one side of the latch element 23 so as to limit its swinging movement in one direction. A suitable spring pressed abutment 27 is arranged on the plate 25 at the opposite side of the latch element 23 and engages it so as to hold it against the abutment 26 with yielding pressure.

The other of the arms 20 which is adjacent the opposite or supported end of the ram 5 likewise is similarly pivotally connected to the bed 2 by a yoke 28 and pivot 29 and carries a latch element 30 which is connected to it by a pivot 30b. The latch element 30 extends upwardly through a suitable opening in the bed 2 a short distance above the level thereof, and is adapted, when in latching position, to engage in the latch element 17 by entry into the opening 18, as best illustrated in Fig. 6.

Connected to the lever 19 near the juncture of the arms 20 is a piston 31 which operates in a reversible fluid pressure operated cylinder 32 which, in turn, is connected to the frame 1 by means of a pivot 33. The piston and cylinder are arranged to operate so that the piston is raised on the power stroke. Thus the lever 19 fulcrums about the pivots 22 and 29 on the power stroke and draws the latch elements 23 and 30 downwardly. As mentioned, the latch elements 23 and 30, when in raised position, extend only a short distance above the level of the bed 2 so that, when the ram is raised to separate the dies a slight amount, it is dis-

posed above the latch elements 23 and 30 a distance such that adequate access to the space between the ram and bed is provided between the free end of the ram and the bed.

The latch elements 23 and 30 are normally held by the piston 31 in raised position above the level of the bed such that when the ram is lowered near to its final forming position by the piston 12, the latch elements 23 and 30 can engage the latch elements 15 and 17, respectively, so as to interlock therewith, whereby the piston 31 can pull the ram downwardly by equalized pressure applied on the ends of the ram.

The latch element 23 normally remains in its upright position with little or no movement about its pivot 24. Accordingly, to provide for unlatching the latch elements 15 and 23 prior to raising of the ram 5, the latch element 15 must be swung from its dependent position upwardly and outwardly laterally of the ram. For this purpose, a suitable link, as shown, is pivotally connected at one end to the latch element 15 and at the opposite end to a suitable power operated piston or plunger, such as a fluid pressure operated piston or a solenoid operated plunger. In the form illustrated, the link is connected to the piston 34 of a reversible fluid pressure operated piston and cylinder assemblage having a cylinder 35, the piston 34 operating in the reversible cylinder which is mounted on the ram.

As more fully explained hereinafter, the piston 34 not only retracts the latch element 15 to unlatching position, but, during lowering of the ram, yieldably holds the element 15 in its normal dependent latching position.

Since the latch element 17 is fixed in position, it is necessary to swing the latch 30 out of its normal upright position to unlatch it. For this purpose, a reversible, fluid pressure operated piston and cylinder assemblage is provided. The piston 36 of this assemblage is pivotally connected at one end to the frame 1. The cylinder 37 is pivotally connected to the latch element 30. As in the case of the latch element 15, the assemblage not only retracts the element 30 to unlatching position but also, during lowering of the ram, yieldably holds the element 30 in its normal upright latching position.

The latch element 15 has a cam surface 15a on its lower face and the latch element 23 has a cam surface 23a on its upper face. The surfaces 15a and 23a are arranged to engage and swing the latch element 15 out of its depending latching position against the resilient force of the piston 34 upon movement of the ram 5 downwardly from its raised position to a position near to its forming position and prior to operation of the piston 31 on its power stroke. Upon continued downward movement of the ram, the latch element 15 is snapped back into latching position by the piston 34 after relative passage of the lower latching end of the element 15 downwardly beyond the upper latching end of the element 23.

Correspondingly, the latch elements 30 and 17 have cam surfaces 30a and 17a, respectively, which cooperate in like manner to displace the element 30 from its latching position against the resilient force of the piston 36 so as to permit relative passage of the elements 30 and 17 during downward movement of the ram. The latching element 30 is snapped back into latching position by the piston 36 after relative passage of the adjacent ends of the elements 17 and 30.

In operation of the structure thus far described, the ram is lowered rapidly to a position close to the final forming position by means of the piston 12. As it approaches forming position, the cam surfaces 15a and 17a of the latch elements 15 and 17 engage the cam surfaces 23a and 30a of their complementary latch elements 23 and 30, respectively, whereupon the latch elements 23 and 30 are swung out of latching position. Upon continued lowering of the ram, the elements 23 and 30 are returned by their respective piston and cylinder assemblages into latching position in which the arms 20 of the lever 19 are latched to the opposite ends of the ram, respectively. Thereupon the piston 31 is operated upwardly to move the ram 5 downwardly by applying equalized pressure through the arms 20 to the opposite ends of the ram 5. The cylinder 32 may be a higher pressure cylinder than the cylinder 18, or it may be operative at the same pressure, but since only a slight additional movement of the ram by the piston 31 to final closing position is necessary, a large mechanical advantage is given to the piston 31 through the lever 19 and latches 23 and 30, thus applying to the ram a much greater forming pressure than that which could be applied by the direct acting piston 12. Also, since the reactive forces to the downward pull on the latches and upward thrust of the piston 31 is resisted by the bed adjacent the dies, due to the position of the yokes 21 and 29, the major stresses are better localized so that parts of the apparatus not directly involved are relieved from the heavier stresses.

As mentioned the preferred embodiment of the apparatus is in the form of a combined press and tangent bender. For the tangent bending operation, the press is provided with wing dies 40. For mounting the wing dies, a suitable wing die carriage 41 is provided and extends lengthwise of the ram for substantially the full length of the bed 2 along one side of the frame. The carriage 41 is provided at its ends with arms 42 by which it is connected to suitable supports 43 on the bed by means of pivots 44. Normally, the carrier 41 depends from the pivotal connections below the level of the bed and lies alongside of one side of the frame 1, as illustrated in Fig. 1, and it is adapted to be swung upwardly on its forming stroke.

Mounted within the carriage 41 and substantially coextensive in length therewith is a roller 45. The roller is movable transversely of its axis in the carriage 41 toward and away from the pivotal axis. As better illustrated in Fig. 8, this is accomplished by mounting the ends of the roller 45 in suitable bearings 46 which, in turn, are mounted in the carriage 41 for sliding movement toward and away from the pivotal axis of the carriage in suitable slideways and are urged toward the pivotal axis of the carriage by springs 47. Carried by the carriage 41 is a rocker plate 48 which is normally horizontal and faces upwardly and has a channel 49 on its under face in which the roller 45 rolls, the end walls of the channel engaging shoulders on the roller 45, as best indicated at 50, in Fig. 8, so as to prevent endwise movement of the plate 48 in the carriage. The plate 48 is provided with arms 52, the upper edges of which are in the form of racks 53. The racks, in turn, engage suitable gear segments 54 secured to the frame and coaxial with the pivots 44, thus guiding the rocker plate 48 as it is rocked from the position illustrated in

Fig. 1 upwardly and along the lateral faces of the male dies 6.

Any suitable power means may be used to operate the carriage 41 and, as best illustrated in Fig. 7, this is accomplished by means of a piston 55 operating in a reversible fluid pressure cylinder 56, the piston being connected to the carriage 41 and the cylinder being connected to a suitable post 57 secured in fixed position relative to the frame 1. Upon swinging of the carriage 41 upwardly about the axis of the pivots 44, the plate 48 and the wing dies 40 carried thereby are rocked from their horizontal position, illustrated in Fig. 1, upwardly around the rounded lateral edges of the dies 6 into a position such that they form and lay the stock to be formed around such edges and along the lateral faces of the dies 6.

Thus, in order to form a piece of stock into the front, sides and all or marginal portions of the rear wall of a cabinet, the stock is laid in position on the one of the female dies 3, which is nearer the supported end of the ram 5 with one overhanging the adjacent wing die 40. The ram is moved downwardly rapidly by the piston 12 to a piston in which it is engaged by the latches 23 and 30 after which it is moved downwardly more slowly, but with greater pressure, by the piston 31, thus forming the portion of the stock between a male die 6 and a female die 3. While the stock is so held, the carriage 41 is swung upwardly by the piston 55, thus rocking the wing dies upwardly and forming the stock about the adjacent rounded lateral edge and side face of the associated die 6. The wing dies are then swung downwardly and the piston 31 reversed, after which the latches 23 and 30 are released and the ram raised thereafter by the piston 12.

Referring next to Fig. 9, there is illustrated diagrammatically the control means for operation of the apparatus in the cycle described. As there illustrated, two solenoid operated control valves 60 and 61 are provided, the valves being connected to a source of air, or other fluid pressure, and to atmosphere, or a sump. Air pressure is preferred due to its rapid operation and such is used hereinafter for purposes of illustration. The valve 60 is connected to the lower end of the cylinder 13 by a pipe line 62 and to the lower end of the cylinder 35 which operates the latch element 15, and also to the upper end of the cylinder 37 which operates the latch element 30, by branches 62a leading from the pipe line 62. The valve 61, on the other hand, is connected to the upper end of the cylinder 13 by a pipe line 64, and to the upper end of the cylinder 35 and the lower end of the cylinder 37 by branches 64a leading from the line 64.

The valve 60 normally is open so as to admit air under pressure concurrently through the line 62 and its branches 62a to the cylinders 35, 37 and 13 so that the piston 12 is operated to raise the ram 5 and the latches 15 and 30 are moved to unlatched position, concurrently. The valve 60 is movable to a closed position to connect the line 62 and its branches 62a to the atmosphere.

The valve 61, on the other hand, is normally closed and when closed, connects the line 64 and its branches 64a with the atmosphere and when open, connects the line 64 and its branches 64a to pressure.

A solenoid operated valve 65 also is provided and is normally open. When open, it connects the upper end of the cylinder 32 to a source of air pressure through a line 66 and connects the lower end of the cylinder 32 to atmosphere by

5 a line 67. Since normally it is in a position in which air pressure is admitted through the line 66 to the top of the cylinder 32, the arm 19 is held in position in which the latch elements 23 and 30 are in their uppermost position.

6 The valves 60 and 61 are operated by solenoids 68 and 69, respectively, which are connected in parallel across the power lines L¹ and L². A suitable switch 70 is provided in the line L¹ and may 10 be in the form of a self-restoring push button switch or drum type switch, as desired. The valve 65 is operated by a solenoid 71 which is connected to the line L² and through a limit switch 72 to the line L¹, thus being connected in 15 parallel with the solenoids 68 and 69 but in series with the limit switch 72. The limit switch 72 is normally open and self-restoring. For illustration it is shown as held open by a spring 73.

7 A collar 74 is provided on the piston 12 and 20 is arranged to engage and close the switch 72 when the ram has been moved downwardly by the piston 12 to a position in which the latches 23 and 30 can engage the latches 15 and 17, respectively.

25 As illustrated in Fig. 9, the parts thus described are in the normal idle position in which the air under pressure is applied as indicated by the arrows. In this position, the ram is elevated, the latches 15 and 30 are swung out of latching position and the latch 23, along with the latch 30, are in elevated position. The die space between the ram and bed is easily accessible for unloading past the free end of the ram. Upon closure of the switch 70, the solenoid 68 is energized and operates the valve 60 to connect the lines 62 and 62a to the atmosphere. At the same time, the solenoid 69 operates the valve 61 to disconnect the line 64 and branches 64a from the atmosphere and connect it to the source of air pressure. Thereupon, air under pressure is admitted to the top of the piston 12, forcing the ram downwardly at a relatively rapid speed and at the same time the latch elements 15 and 30 are swung to their normal position for latching and are 30 yieldably held in such position by their respective pistons and cylinders. The ram continues moving downwardly on the rapid traverse stroke until it is close to the forming position. As it approaches this position the latches 15 and 17 have passed the upper ends of the latch elements 23 and 30, this relative passage having been effected by movement of the latch 15 and the latch 30 out of the respective paths of the latches 23 and 17 due to camming action of the complementary cam surfaces of the latches and the return of the elements 15 and 30 by their respective pistons. After the latches are in position for latching, the collar 74 engages and closes the limit switch 72. As soon as the limit switch 72 is closed, the solenoid 71 operates the valve 65 to disconnect the line 66 from the source of air pressure and to connect it to the atmosphere and concurrently to connect the line 67 to the source of air pressure, thus lifting the piston 31 and forcing the latches downwardly on the forming stroke with greater pressure than would be provided by the cylinder 13.

70 When the switch 70 is released it disconnects all of the solenoids from the source of electric power and the valves 60, 61 and 65, being self-restoring sequentially, return to their starting position, thus first releasing the latch elements 15 and 30 and then raising the ram. The wing dies are then operated by a circuit, next to be

described, prior to release of the valve 70 so that the stock is formed by the wing dies while gripped between the dies 6 and 40.

The piston 56, for operating the wing dies, is separately controlled by means of a solenoid operated valve 75 which is also connected to the source of air pressure and to the atmosphere. Normally, the valve 75 connects the cylinder 56 above the piston, through the line 76, to the source of air pressure, and connects the cylinder 56 below the piston to the atmosphere, through the line 77, thus holding the wing dies in the downward or retracted position. Reversal of the valve 75 connects the upper end of the cylinder to the atmosphere through the line 76 and connects the lower end of the cylinder to the source of air pressure through the line 77, thus moving the piston upwardly and thereby moving the wing dies on their forming stroke. A solenoid 78 is provided for operating the valve 75 and is connected across the lines L¹ and L² through a switch 79 which may be of the self-centering drum type or of the self-restoring push button type, and which is normally open.

Referring next to Figs. 10 and 11, a machine of the same general character is illustrated. In this form of the invention, the ram 80 is mounted on a suitable post 81 which is vertically reciprocable in bearings 82 in the frame 83. At the free end of the ram there is mounted in the bed of the frame 83 a vertically reciprocable post 84 which is guided in bearings 85 in the frame. The column 81 is connected by a toggle link 86 to a piston 87 operating in a reversible cylinder 88. The post 84 is similarly connected by a toggle link 89 to a piston 90 operating in a reversible cylinder 91. The cylinders 88 and 91 are pivotally connected to the frame and through suitable valves, not shown, can be connected to the source of fluid pressure so as to admit fluid pressure to both cylinders concurrently or independently for expanding the links concurrently and selectively and for contracting the links concurrently and selectively. The post 84 is arranged to engage a socket 92 in the free end of the ram and is provided with a suitable notch 93 which, when the post is fully inserted, is in a position for latching to the free end of the ram. A suitable rotatable eccentric cam 94 is mounted in the free end of the ram and is arranged to be operated by a lever 95 to a position in which it engages and disengages the notch 93.

In operation of this modification, fluid pressure is admitted only to the cylinder 88 so as to raise the ram 80 while the post 84 is unlatched from the ram, the cylinder 91 being connected to the source of fluid pressure so as to hold the post 84 in retracted position. Thereupon, formed stock interposed between the ram and bed can be withdrawn between the bed and free end of the ram. Next, while retaining the ram in raised position, a piece of stock is inserted between the dies by passing it between the ram and top of the post 84, or by inserting it from the side, as desired. The valve for the cylinder 91 then is operated so as to expand the linkage 89 and thereby raise the post 84 into position for latching, whereupon it is latched by downward movement of the lever 95. Next, the valves are operated to admit fluid pressure to both cylinders 88 and 91 concurrently so as to retract the linkages 86 and 89 and thereby lower the post 84 and column 81 concurrently for forming the piece.

It will be noted that in both forms of the invention, the ram and bed are sufficiently long to

accommodate either a very long set of dies or two sets of dies spaced apart endwise of the ram. In using two sets of dies and a single wing die carrier, the operation for forming the front, rear, and margins of the rear wall of a cabinet are as follows: A sheet of stock can be inserted from the side of the machine between the set of dies nearer the supported end of the ram and the sheet crowned and formed between the male die 6 and female die 3 of that set, and one overhanging end thereof formed by the adjacent cooperating wing die 40 while the stock is gripped between the male and female die. When the ram is raised, the piece thus formed is removed laterally of the ram and is reversed in position and inserted through the space between the free end of the ram and the bed into position in the set of dies which is nearer the free end of the ram, and a new piece inserted laterally of the ram, between the set of dies near the supported end of the ram. Upon the next downward movement of the ram, another piece of stock near the supported end is formed as already described. At the same time, the piece of stock between the set of dies adjacent the free end of the ram, is finish formed, the other overhanging end of the stock being bent up by the wing die 40 against the free end of the ram. When the ram is next raised, the piece finally formed between the dies adjacent the free end of the ram can be removed endwise of the ram through the space between the free end of the ram and the bed.

It is apparent with the apparatus described that articles such as cabinet portions and the like, even those which are peripherally closed, can readily be formed and easily removed from the apparatus.

Since equalized ram operating pressure is applied to both ends of the ram, deflection of the ram is negligible.

Further it is apparent from the foregoing description that if desired for more rapid production a duplicate set of wing dies can be provided at the opposite side of the press and the wing dies at opposite sides of the press can be operated concurrently.

Furthermore, in event that cabinets of square cross section and the like are to be formed with relatively sharp edges the usual bending brake dies can be substituted for the forming dies described and the press used as a conventional bending brake without the necessity for wing dies.

In the description and claims, the structures are described by reference to a horizontal frame, using words such as "upwardly," "downwardly," "above," "below" and the like. It is to be understood that these terms are used in a relative sense only for convenience in description of the relative positions of various parts to each other and not their positions with respect to an actual vertical or horizontal plane.

Having thus described our invention, we claim:

1. In a forming machine, a frame having an upwardly facing work bed adapted to accommodate a working tool, a ram adapted to carry a downwardly facing complementary working tool, means connecting one end of the ram to the frame and supporting and guiding the ram for movement along a generally upright lineal path from a position above the bed downwardly toward, and upwardly away from, the plane of the bed, latching means on the ram near the other end of the ram, said other end of the ram and its latching means normally being free and dis-connected from the frame so as to afford access

to the space between the bed and ram from the free end of the ram, tension applying means, including cooperable latching means near the free end of the ram, mounted on the frame for movement upwardly and downwardly relative to the plane of the bed and to a position in which it is spaced below the level of the ram and its latching means, when the ram is in a predetermined raised position, so as not to obstruct said access to the space between the ram and bed from said free end of the ram, said cooperable latching means of the tension applying means and latching means of the ram being engageable with, and disengageable from, each other, selectively, for latching the tension applying means and free end portion of the ram for movement together in a direction to move the ram toward the plane of the bed and for unlatching them for independent movement, and power means operatively connected to the tension applying means for moving the tension applying means and thereby said one end of the ram downwardly toward the plane of the bed.

2. In a forming machine, a frame having an upwardly facing work bed adapted to accommodate a working tool, a ram adapted to carry a downwardly facing complementary working tool, means connecting one end of the ram to the frame and supporting and guiding the ram for movement along a generally upright lineal path from a position above the bed downwardly toward, and upwardly away from, the plane of the bed, latching means on the ram near the other end of the ram, said other end of the ram and its latching means normally being free and disconnected from the frame so as to afford access to the space between the bed and ram from the free end of the ram, power means operatively connected to the ram and operable to move the ram along said path toward and away from the plane of the bed, tension applying means, including cooperable latching means near the free end of the ram, mounted on the frame for movement relative to the frame and ram upwardly toward, and downwardly from, the ram and to a position in which it is spaced below the level of the ram when the ram is in a predetermined raised position so as not to obstruct said access to the space between the ram and bed from said free end of the ram, said cooperable latching means of the tension applying means and the latching means of the ram being engageable with and disengageable from each other, selectively, for latching the tension applying means and free end portion of the ram for movement together in a direction to move the ram toward the plane of the bed and for unlatching them for independent movement, and power means operatively connected to the tension applying means for moving the tension applying means and thereby said free end of the ram downwardly toward the plane of the bed.

3. In a forming machine, a frame having an upwardly facing work bed adapted to accommodate a working tool, a ram adapted to carry a downwardly facing complementary working tool, latching means on opposite end portions of the ram, respectively, means connecting one end of the ram to the frame and supporting and guiding the ram for movement along a generally upright lineal path from a position above the bed downwardly toward, and upwardly away from, the plane of the bed, the other end of the ram and its latching means normally being free and disconnected from the frame so as to afford

access to the space between the bed and ram from the free end of the ram, tension means mounted on the frame for movement upwardly and downwardly, said tension means including cooperable latching means positioned near opposite end portions of the ram, respectively, said tension means and its cooperable latching means near the free end portion of the ram being movable to a position in which they are spaced below the level of the ram and the latching means on the free end portion of the ram, when the ram is in a predetermined raised position relative to the plane of the bed, so as not to obstruct said access to the space between the ram and bed from the free end of the ram, said latching means of the opposite end portions of the ram and the respective cooperable latching means of the tension means being engageable for latching the tension means to the end portions, respectively, for movement together in a direction to move the ram toward the plane of the bed, power means connected to the tension means for moving the tension means and thereby moving the ram downwardly while the tension means is latched to the ram.

4. In a forming machine, a frame having an upwardly facing work bed adapted to accommodate a working tool, a ram adapted to carry a downwardly facing complementary working tool, means connecting one end of the ram to the frame and supporting and guiding the ram for movement along a generally upright lineal path from a position above the bed downwardly toward, and upwardly away from, the plane of the bed, the other end of the ram normally being free and disconnected from the frame so as to afford access to the space between the bed and ram from the free end of the ram, power means for moving the ram downwardly to a predetermined position above the bed, tension means movably mounted on the frame, means on the tension means readily connectible to and detachable from the free end portion of the ram and operable, when connected to the ram, to pull the ram downwardly upon movement of the tension means in said direction, and additional power means operable for moving the tension means in said direction so as to move the ram downwardly thereby.

5. In a forming machine, a frame having an upwardly facing work bed adapted to accommodate a working tool, a ram adapted to carry a downwardly facing complementary working tool, means connecting one end of the ram to the frame and supporting the ram above the bed for movement along a generally upright lineal path downwardly toward, and upwardly away from, the plane of the bed, respectively, the other end of the ram normally being free and disconnected from the frame so as to afford access to the space between the bed and ram from the free end of the ram, a bifurcated lever pivotally connected to the frame for rocking about an axis extending generally parallel to the ram and having free end portions adjacent opposite ends of the ram, respectively, and positioned there beneath, latch means on said free end portions, respectively, complementary latch means on the opposite ends of the ram, respectively, complementary to the first latch means, means operable to latch the first latch means to the complementary latch means and to unlatch the same, selectively, and a reversible power means connected to said bifurcated lever and operable to rock said lever about its said pivotal axis for ap-

plying the power of said power means equally to opposite ends of the ram when the first latch means and complementary latch means are in latching engagement.

6. In a forming machine, a frame having an upwardly facing work bed adapted to accommodate a working tool, a ram adapted to carry a downwardly facing complementary working tool, latch means on opposite end portions of the ram, respectively, means connecting one end of the ram to the frame and guiding and supporting the ram for movement along a generally upright linear path from a position above the bed downwardly toward, and upwardly away from, the plane of the bed, respectively, the other end of the ram and its latch means normally being free and disconnected from the frame so as to afford access to the space between the bed and ram from the free end of the ram, power means operatively connected to the ram and operable selectively to move the ram along said path toward and away from the plane of the bed, tension means movably mounted on the frame, and including complementary latch means carried thereby adjacent the opposite ends of the ram, respectively, said complementary latch means being operable to be engaged in latching relation to, and disengaged from, the first latch means, selectively, additional power means operatively connected to the tension means and operable to move the tension means for moving the ram downwardly when the complementary latch means of the tension means and the latch means of the ram are in latching engagement.

7. A structure according to claim 6 characterized in that control means are provided for operating the first power means in opposite directions, selectively, additional control means are provided for operating the additional power means in opposite directions, selectively, and control mechanism is provided which operatively interconnects said control means so as to render the second control means operative to cause the said additional power means to move the ram downwardly consequent upon movement of the ram

downwardly to a predetermined position by the first power means.

8. The forming machine according to claim 6 characterized in that at least one of the movable tension means and additional power means includes means operative to cause the tension applying means to exert a greater force on the ram for moving the ram toward the bed than the force exerted on the ram by the power means of the ram for moving the ram toward the bed.

9. The forming machine according to claim 6 characterized in that at least one of the movable tension means and additional power means includes means operative to cause the tension means to move the ram toward the bed at a lesser rate of speed than that at which the ram is moved toward the bed by the power means of the ram.

10. The forming machine according to claim 6 characterized in that at least one of the movable tension means and additional power means includes means for equalizing the respective forces applied by the tension means to the respective ends of the ram for moving the ram toward the bed.

11. The structure according to claim 6 characterized in that said complementary latch means of the tension means are so selectively connectable to, and disconnectable from, the latch means of the ram during movement of the ram along said path.

12. The structure according to claim 1 characterized in that the tension applying means and its complementary latching means are movable, relative to the ram, to and from the position in which they are spaced from the ram and its latching means, during movement of the ram along said path.
